UNITED STATES PATENT OFFICE

GEORGE H. ECKERT, OF SYRACUSE, NEW YORK, ASSIGNOR TO HUMPHREY GAS PUMP COMPANY, A CORPORATION OF NEW YORK.

PRESSURE CONTROL IN PUMPING.

1,228,419.

Specification of Letters Patent.

Patented June 5, 1917.

Application filed May 27, 1915. Serial No. 30,729.

To all whom it may concern:

Be it known that I, GEORGE H. ECKERT, a citizen of the United States, residing at Syracuse, in the county of Onondaga, State of New York, have invented a new and useful Pressure Control in Pumping, of which the following is a specification.

The invention relates to moving or forcing liquids and is especially applicable to that form of method and means wherein the body of liquid is caused to reciprocate, one movement of said reciprocation being due to an expansible charge, and wherein a movement of the liquid and the momentum acquired thereby, is utilized to compress a fresh charge. The object of the invention is to prevent excessive compression when the liquid is forced to a relatively high head.

The ordinary simple form of Humphrey pump is to a great extent limited in the head to which it can deliver liquid, by the amount of compression caused by the return of the liquid column. When this compression becomes excessive, splashing ensues and therefore thirty-five feet is approximately the highest lift that has been accomplished up to the present time.

Referring to the drawing which illustrates, merely by way of example, a suitable embodiment of my invention, the figure is a diagrammatic elevation showing the application of my invention to the ordinary Humphrey pump.

1 indicates the power chamber, 2 the intake valves, 3 the play pipe, 4 the normal level of the liquid supply, 5 the height to which the water would rise due to atmospheric pressure if there is a vacuum in the play pipe above it. 6 are the discharge valves, 7 the delivery outlet. 8 is an air chamber to be used when it is desired to have a partial vacuum only in the play pipe. 9 is a check valve, and 10 is a stop valve for controlling an air inlet, which forms another means for reducing the vacuum in the play pipe by admitting air.

If there is a vacuum in the play pipe the water will stand at the level 5, 5 when at rest so that when on the return stroke only the water falling from the level of the valves 6 to the level 5, 5 will be effective in compressing a charge in 1, as the water below 5, 5 will be balanced by atmospheric pressure.

55 The action of this pump is the same as

any Humphrey pump, except that when the water comes to rest on the outstroke the delivery valves 6 close and prevent air from rushing back into the play pipe. A vacuum or partial vacuum will be formed above the water column and the return of the water retarded thereby reducing the compression in 1, and also reducing the inertia to be overcome upon the next power stroke. By this means an additional head of approximately thirty feet may be obtained without causing an excess of compression, or other complication in operating the pump.

If the arrangement as described reduces the compression too much, this can be modified either by placing an air chamber such as 8, in connection with the play pipe, so that a perfect vacuum cannot be formed; or else by admitting air, as through valves 9 and 10, into the play pipe beneath the valves 6.

The above examples are given merely as specific instances of method and means for modifying the force or pressure of the return stroke when pumping against relatively high heads. It is conceivable that other means may be employed which would be equally within the scope of the invention, as defined in the accompanying claims:

What I claim is:

1. The method which consists in reciprocating a column of liquid with a velocity sufficiently limited to preserve the coherence of the column and having sufficient bulk and path of travel to acquire useful momentum, utilizing an expansive force to cause one stroke of said reciprocation, and restraining a return stroke by a below atmospheric pressure to the rear of the column in order to reduce the pressure developed.

2. The method which consists in reciprocating a column of liquid with a velocity sufficiently limited to preserve the coherence of the column and having sufficient bulk and path of travel to acquire useful momentum, utilizing an expansive force to cause one stroke of said reciprocation, and reducing the velocity of the return stroke by a below atmospheric pressure to the rear of the column.

3. The method which consists in reciprocating a column of liquid with a velocity sufficiently limited to preserve the coherence of the column and having sufficient bulk and path of travel to acquire

useful momentum, utilizing an expansive force to cause one stroke of said reciprocation, discharging a portion of the liquid at the required head and utilizing a partial vacuum above the liquid column beneath the point of discharge, by preventing air from entering the space vacated by the returning column, to retard the return stroke.

10 4. The method which consists in reciprocating a column of liquid with a velocity sufficiently limited to preserve the coherence of the column and having sufficient bulk and path of travel to acquire 15 useful momentum, utilizing an expansive force to cause one stroke of said reciprocation, to force the liquid to the required head or pressure and utilizing a vacuum above the liquid column, by preventing air 20 from entering the space vacated by the returning column, to retard the return stroke, and thereby reduce the pressure to be overcome upon the next power stroke.

5. The combination of a power chamber, 25 a play pipe for the reciprocation of liquid in operative relationship therewith, said play pipe provided with liquid intake valves and liquid discharge valves, the latter being placed near the upper end of 30 the play pipe and arranged to close after the discharge of liquid therethrough and thereby cause a vacuum or partial vacuum on top of the liquid column upon its return stroke in order to retard said return 35 stroke.

6. The combination of a power chamber, a play pipe for the reciprocation of liquid in operative relationship therewith, said play pipe provided with liquid intake 40 valves and liquid discharge valves, the latter being placed near the upper end of the play pipe and arranged to close after the discharge of liquid therethrough and thereby cause a vacuum or partial vacuum 45 on top of the liquid column, by preventing air from entering the space vacated by the returning column, in order to retard said return stroke, and an air chamber connected with the play pipe just beneath the 50 discharge valves for modifying said vacuum.

7. The combination of a power chamber, a play pipe for the reciprocation of liquid in operative relationship therewith, said play pipe provided with liquid intake 55 valves and liquid discharge valves, the latter being placed near the upper end of the play pipe and arranged to close after the discharge of liquid therethrough and thereby cause a vacuum or partial vacuum 60 on top of the liquid column, by preventing air from entering the space vacated by the returning column, in order to retard said return stroke and a valve controlled air intake connected with the play pipe beneath the discharge valves for modifying the vacuum caused by the return stroke.

8. The combination of a play pipe, for the reciprocation of liquid and a power chamber in operative relationship therewith, the play pipe provided with liquid intake and discharge, the discharge being at a point elevated above the intake, as means whereby the liquid is made to reciprocate, one stroke of said reciprocation 75 being due to the expansion of a primary medium in the power chamber, a return stroke being due to a part of the head or pressure to which the liquid has been forced, and means forming a vacuum 80 above the liquid column for retarding the return stroke in order to modify the compression caused thereby.

9. The combination of a play pipe for the reciprocation of liquid and a power chamber in operative relationship therewith, the play pipe provided with liquid intake and discharge, the discharge being at a point elevated above the intake, as means whereby the liquid is made to reciprocate, one stroke of said reciprocation 85 being due to the expansion of a primary medium in the power chamber, a return stroke being due to a part of the head or pressure to which the liquid has been 90 forced, and means below atmospheric pressure above the liquid column for modifying the force of the return stroke.
